UNITED STATES PATENT OFFICE.

JOHN H. HUNT, OF DAYTON, OHIO, ASSIGNOR TO THE DAYTON ENGINEERING LABORATORIES COMPANY, A CORPORATION OF OHIO.

CIRCUIT-BREAKER-INDICATING DEVICE.

Application filed August 13, 1919. Serial No. 317,193.

To all whom it may concern:

Be it known that I, JOHN H. HUNT, a citizen of the United States of America, residing at Dayton, county of Montgomery, 5 State of Ohio, have invented certain new and useful Improvements in Circuit-Breaker-Indicating Devices, of which the following is a full, clear, and exact description.

This invention relates to improvements in 10 circuit breaker indicating devices for use in electrical systems, and is adapted to indicate the existence in said system of abnormal conditions of the current. This invention relates more particularly to improvements in 15 circuit breaker indicating devices of the type disclosed in patent of C. F. Kettering, No. 1,836,143, dated April 6, 1920. In the patent referred to it was one of the objects of the invention to provide a circuit breaker 20 which has provisions for retarding the operation of the circuit breaker in such a manner as to provide a clear and unmistakable signal to indicate to the operator that abnormal conditions exist in the circuit, and at 25 the same time to prevent the waste of current. The invention disclosed in the patent referred to included an electromagnetic circuit breaker of the vibrating type including a coil connected with the electrical systems 30 and a core of magnetic material. This electromagnetic structure effected the attraction of an armature which separated a pair of contacts also connected in the system and in series with said coil. Upon interruption of 35 the current flow through said coil the magnetic device would become demagnetized and the armature would be moved away from the magnet core through the action of a spring to effect the reengagement of the contacts of 40 the circuit breaker whereupon the operation would be repeated.

The succession of blows of one of the breaker contacts upon the other created an 45 audible signal which would indicate to the attendant that an abnormally low resistance to current flow existed in the electrical system. In order to make this signalling device the more effective the electromagnet was provided with a retarding device in order that the engagement of the contacts 50 would not take place too rapidly but in such a manner that a clicking rather than a buzzing sound would be produced. This retarding device comprised a copper sleeve inter- 55 posed between the magnet coil and the core

of magnetic material. The function of this copper sleeve was to retard the demagnetizing of the electromagnet upon cessation of current in the magnet coil.

It has been found that under certain conditions that the copper sleeve about the magnet core tends to retard the magnetization of the core and allows the current in the system to build up to a very high value before the armature begins to move.

It is an object of the present invention to overcome this difficulty by providing means by which the increasing of flux through the armature which separates the contacts will lag very little behind the increasing of current in the magnet coil. In this manner the circuit breaker indicating device will commence to function sooner upon an abnormal rise of current in the system than in the case where the lag of magnetization of the core is relatively great.

Other and further objects of the present invention will be apparent from the following description, reference being had to the accompanying drawings, wherein preferred forms of embodiments of the present invention are clearly shown.

In the drawings:

Fig. 1 is a longitudinal sectional view of a structure embodying the invention together with a wiring diagram;

Fig. 2 is a side view looking in the direction of the arrow 2 of the structure shown in Fig. 1; and

Fig. 3 is a view similar to Fig. 1 showing a modified form of the invention.

In the drawings, 20 designates a frame of magnetic material provided with outwardly projecting ears 21 which are notched at 22 for a purpose to be described. Said frame 95 supports a core of magnetic material 23 upon which is mounted a spring stud 24 of non-magnetic material. A sleeve 25 of non-magnetic material of good electrical conductivity such as copper is placed about the core 23, and a second sleeve 26 or core of magnetic material such as steel is placed about the sleeve 25. An insulating sleeve 27 surrounds the sleeve 26 and around this sleeve 27 are wound the turns of the magnet coil 28.

One end of coil 28 is connected with a terminal 29 and the other end with a conducting strip 30 which supports a contact 31. Contact 31 is normally engaged by contact 110

32 mounted upon a leaf spring 33 of conducting material which is mounted upon an insulating block 34 secured to the frame 20. Spring 33 is provided with a terminal portion 35 which may be connected with a switch 36 which in turn is connected with battery 37. Terminal 29 may be connected with a circuit including lamps 38 or other electrical translation devices. This circuit 10 38 has a ground connection with a battery indicated by numerals 39 and 40.

An armature 41 is provided with outwardly projecting ears 42 which are located within the notches 22 provided in ears 21. 15 Armature 41 is provided with an aperture 43 through which the stud 24 projects and said armature is bent around to provide a portion 44 which is arranged to engage a button of insulating material 45 mounted 20 upon the spring 33. Armature 41 is also formed to provide a stop portion 46 normally engaging the insulating block 34. A leaf spring 47 is secured at one end upon the armature 41 by a rivet 48 and the other 25 end of said spring 47 is apertured to provide for the projecting therethrough of the reduced upper end of stud 24. The reduction of upper end of stud 24 provides a shoulder against which said spring 47 rests, 30 whereby said spring normally maintains the armature in the position shown in Fig. 1.

The operation of the invention is as follows:

In order to operate the lamps 38 the 35 switch 36 is closed. The circuit breaker is constructed so that the normal flow of current to these lamps will not cause sufficient attraction of the armature 41 to cause it to move. If for any reason an abnormal flow 40 of current through the indicating device should occur, as by reason of a short circuit existing between the indicating device and the lamp circuit, this abnormal flow of current will cause the attraction of the armature. 45 Since the sleeve 26 is not surrounded by any non-magnetic conducting sleeve, such as sleeve 25, the magnet will operate quickly to attract the armature 41. Upon attraction of armature 41, the contacts 31 and 32 will 50 be separated and current will cease to flow through the magnet coil 28. As soon as this current ceases to flow there is a tendency for the core to become demagnetized and for the spring to draw the armature back again to 55 its normal position, at which time the lamp circuit will be again established. By reason of the existence of the sleeve 25, which is preferably of copper, there will be a retardation of the demagnetization of the core or a 60 sustaining of the flux in the core by means of an electrical effect which is set up in the closed metallic circuit formed by this copper sleeve. The effect of this delay of demagnetization of the core 23 tends to hold 65 the armature in its attracted position even

after the circuit is broken, so that it may be said that the magnetic effect of the core 23 is prolonged sufficiently to make the successive vibratory movements of the armature at less frequent intervals than would be possible if the copper sleeve were omitted. The object of this feature of the invention is to make the blows produced by the impact of contact 32 upon contact 31 more clear and distinct, and also to save current by prolonging the interval of separation of the contacts 31 and 32. 75

As previously explained in the copending patent referred to it will be obvious that if the lamp circuit is broken and made successively, but with a long interval between each of the successive breaks of the circuit, the clicking of the circuit breaker will tend audibly to indicate the existence of trouble 80 in the electrical system. 85

The present invention possesses all of the advantages of the invention disclosed in the application referred to, and also the additional advantage that, when the condition of the electric circuit is such as to permit an exceedingly rapid rise of current when the contacts close, the increase of the pull on the armature to a value sufficient to move it and separate the contacts is not delayed by the means provided to cause the core or cores 90 to have an attraction for the armature after the current has been broken. The advantage of this feature of the present invention results from the fact that when there is a short circuit of very low resistance, a vibrating circuit breaker constructed as described will limit the flow of current to a much lower value as measured by a direct current ammeter, than will a vibrating circuit breaker constructed according to the invention disclosed in the copending application referred to. 100 105

A modified form of the invention is shown in Fig. 3. A frame 20^a of magnetic material is constructed in the manner similar 110 to the construction of the frame 20 of the first form of the invention shown. This frame has a mounting portion which is large enough to support the core 23 and the sleeve 25 hereinbefore described, and an additional 115 core 26^a of magnetic material. A sleeve of non-conducting material 27^a is placed around sleeve 25 and core 26^a, around this conducting sleeve is mounted the circuit breaker winding 28^a. The armature 41^a and the 120 spring 47^a are similar in construction with elements 41 and 47 hereinbefore described but are made longer in order to extend over core 26^a and core 23. 125

The core 26^a has the same function as the sleeve 26 shown in Fig. 1, that is, it provides for the increase of flux through the armature 41^a with relatively little lagging behind the increase in current in coil 28^a, because core 26^a is not surrounded by a short circuited 130

non-magnetic conductor. The sleeve 25 is permitted to function in a manner such as to produce a relatively slow demagnetization of the armature 41^a.

5 In simple language, the present invention provides that the armature shall begin to move to contact separating position, very soon after the abnormal rise in current has occurred, but shall begin to move to normal 10 position a relatively great time after the instant of contact separation.

While the forms of mechanism herein shown and described constitute preferred forms of embodiments of the invention, it is 15 to be understood that other forms might be adopted, all coming within the scope of the claims which follow.

What I claim is as follows:

1. In a vibrating circuit breaker, the combination with cooperating contacts; of means tending to maintain engagement of said contacts; and electro-magnetic means for intermittently separating said contacts when the current passing across them exceeds a 25 certain value, said means including a magnetizable armature, a coil in circuit with said contacts, and a core including a path for effecting the increase of flux through said armature with relatively small lag behind the increasing of current in said coil, and damping means for effecting a decrease of flux through said armature with relatively great lag behind the time of contact separation.

35 2. In a vibrating circuit breaker, the combination with cooperating contacts; of means tending to maintain engagement of said contacts; and electro-magnetic means for intermittently separating said contacts when the current passing across them exceeds a 40 certain value, said means including a magnetizable armature, a coil in circuit with said contacts, and a plurality of cores excited by said coil, one core for effecting the increase 45 of flux through said armature with relatively small lag behind the increasing of current in said coil, and another core having means for effecting the decrease of flux through said armature with relatively great lag behind the time of contact separation.

50 3. In a vibrating circuit breaker, the combination with cooperating contacts; of means tending to maintain engagement of said contacts; and electro-magnetic means for inter-

mittently separating said contacts when the 55 current passing across them exceeds a certain value, said means including a magnetizable armature, a coil in circuit with said contacts, and two cores excited by said coil and a short-circuited conductor in the field of one 60 core but not in the field of the other.

4. In a vibrating circuit breaker, the combination with cooperating contacts; of means tending to maintain engagement of said contacts; and electro-magnetic means for intermittently separating said contacts when the current passing across them exceeds a certain value, said means including a magnetizable armature, a coil in circuit with said contacts, and two cores excited by said coil, and a conducting sleeve of non-magnetic material surrounding one only of the said cores.

5. In a vibrating circuit breaker, the combination with cooperating contacts; of means tending to maintain engagement of said contacts; and armature for separating said contacts; electro-magnetic means including an undamped flux path for effecting, when the current carried by said contacts exceeds a certain value, the movement of said armature to separate said contacts, the lagging of said movement behind the increase of current being relatively small, and flux sustaining means for causing the return movement of said armature to take place with relatively great lagging behind the time of contact separation.

6. In a vibrating circuit breaker, the combination with cooperating contacts; an armature movable to separate the contacts; an electromagnet including a coil and concentrically disposed spaced magnetic cores; and a sleeve of conducting non-magnetic material between said cores.

7. In a vibrating circuit breaker, the combination with cooperating contacts; an armature movable to separate the contacts; an electromagnet including a coil and concentrically disposed spaced magnetic cores; and a copper sleeve between said cores.

In testimony whereof I affix my signature.

JOHN H. HUNT.
